ABSTRACT

A new and distinct cultivar of *Mandevilla* plant named 'Inmanbemag', characterized by its compact to medium in size, broadly upright plant habit; moderately vigorous growth habit and moderate growth rate; freely branching habit; dense and bushy appearance; dark green-colored leaves; early and freely flowering habit; dark red-colored flowers with reddish orange-colored throats; and flowers that typically do not sunscald under high light conditions.

2 Drawing Sheets

1

Botanical designation: *Mandevilla sanderi*.
Cultivar denomination: 'INMANBEMAG'.

**STATEMENT REGARDING PRIOR
DISCLOSURES BY INVENTOR AND
APPLICANT/ASSIGNEE**

An European Community Plant Breeder's Rights application for the instant plant was filed by the Applicant/Assignee of the instant application, Innovaplant Zierpflanzen GmbH & Co. KG of Gensingen, Germany on Oct. 24, 2022, application number 2022/2394. Foreign priority is not claimed to this European Community Plant Breeder's Rights application.

The Inventor and Applicant/Assignee assert that no publications nor advertisements relating to sales, offers for sale or public distribution occurred more than one year prior to the effective filing date of this application. Any information about the claimed plant would have been obtained from a direct or indirect disclosure from the Inventor and/or Applicant/Assignee. Inventor and Applicant/Assignee claim a prior art exception under 35 U.S.C. 102(b)(1) for disclosure and/or sales prior to the filing date but less than one year prior to the effective filing date.

BACKGROUND OF THE INVENTION

The present invention relates to a new and distinct cultivar of *Mandevilla* plant, botanically known as *Mandevilla sanderi* and hereinafter referred to by the name 'Inmanbemag'.

2

The new *Mandevilla* plant is a product of a planned breeding program conducted by the Inventor in Johannesburg, South Africa and Heidesheim, Germany. The objective of the breeding program is to create new freely branching ⁵ *Mandevilla* plants that flower early and freely and have attractive flowers that resist fading and sunscalding.

The new *Mandevilla* plant originated from a cross-pollination conducted by the Inventor in Johannesburg, South Africa in November, 2016 of a proprietary breeding selection of *Mandevilla sanderi* identified as code number D14-3239-1, not patented, as the female, or seed parent with a proprietary breeding selection of *Mandevilla sanderi* identified as code number D14-3060-1, not patented, as the male, or pollen, parent. The new *Mandevilla* plant was discovered and selected by the Inventor as a single flowering plant from within the progeny of the stated cross-pollination in a controlled greenhouse environment in Heidesheim, Germany in June, 2018.

20 Asexual reproduction of the new *Mandevilla* plant by vegetative cuttings in a controlled greenhouse environment in Heidesheim, Germany since June, 2018 has shown that the unique features of this new *Mandevilla* plant are stable and reproduced true to type in successive generations.

25

SUMMARY OF THE INVENTION

Plants of the new *Mandevilla* have not been observed under all possible combinations of environmental conditions

and cultural practices. The phenotype may vary somewhat with variations in environmental conditions such as temperature and light intensity without, however, any variance in genotype.

The following traits have been repeatedly observed and are determined to be the unique characteristics of 'Inmanbemag'. These characteristics in combination distinguish 'Inmanbemag' as a new and distinct *Mandevilla* plant:

1. Compact to medium in size, broadly upright plant habit.
2. Moderately vigorous growth habit and moderate growth rate.
3. Freely branching habit; dense and bushy appearance.
4. Dark green-colored leaves.
5. Early and freely flowering habit.
6. Dark red-colored flowers with reddish orange-colored throats.
7. Flowers typically do not sunscald under high light conditions.

Plants of the new *Mandevilla* can be compared to plants of the female parent selection. Plants of the new *Mandevilla* differ primarily from plants of the female parent selection in the following characteristics:

1. Leaves of plants of the new *Mandevilla* are darker green in color than leaves of plants of the female parent selection.
2. Plants of the new *Mandevilla* flower earlier than plants of the female parent selection.
3. Flowers of plants of the new *Mandevilla* are smaller than flowers of plants of the female parent selection.
4. Flower petals of plants of the new *Mandevilla* are broader than flower petals of plants of the female parent selection.
5. Flowers of plants of the new *Mandevilla* are lighter red in color than flowers of plants of the female parent selection.

Plants of the new *Mandevilla* can be compared to plants of the male parent selection. Plants of the new *Mandevilla* differ primarily from plants of the male parent selection in the following characteristics:

1. Plants of the new *Mandevilla* are larger than plants of the male parent selection.
2. Plants of the new *Mandevilla* are more freely branching than plants of the male parent selection.
3. Leaves of plants of the new *Mandevilla* are larger and lighter green in color than leaves of plants of the male parent selection.
4. Plants of the new *Mandevilla* flower about one week later than plants of the male parent selection.

Plants of the new *Mandevilla* can also be compared to plants of *Mandevilla sanderi* 'Lanidaho', disclosed in U.S. Plant Pat. No. 24,124. In side-by-side comparisons, plants of the new *Mandevilla* differ primarily from plants 'Lanidaho' in the following characteristics:

1. Plants of the new *Mandevilla* are more freely branching and bushier than plants of 'Lanidaho'.
2. Plants of the new *Mandevilla* have larger flowers than plants of 'Lanidaho'.

BRIEF DESCRIPTION OF THE PHOTOGRAPHS

The accompanying colored photographs illustrate the overall appearance of the new *Mandevilla* plant showing the colors as true as it is reasonably possible to obtain in colored reproductions of this type. Colors in the photographs may differ slightly from the color values cited in the detailed

botanical description which accurately describe the actual colors of the new *Mandevilla* plant.

The photograph on the first sheet (FIG. 1) is a side perspective view of a typical flowering plant of 'Inmanbemag' grown in a container.

The photograph on the second sheet (FIG. 2) is a close-up view of a typical flower of 'Inmanbemag'.

DETAILED BOTANICAL DESCRIPTION

The aforementioned photographs and following observations, measurements and values describe plants grown during the summer in 11-cm containers in a glass-covered greenhouse in Heidesheim, Germany and under cultural practices typical of commercial *Mandevilla* production. During the production of the plants, day temperatures ranged from 12 C to 35 C and night temperatures ranged from 12 C to 18 C. Plants were four months old when the photographs and description were taken. In the following description, color references are made to The Royal Horticultural Society Colour Chart, 2015 Edition, except where general terms of ordinary dictionary significance are used. Botanical classification: *Mandevilla sanderi* 'Inmanbemag'. Parentage:

Female, or seed, parent.—Proprietary breeding selection of *Mandevilla sanderi* identified as code number D14-3239-1, not patented.

Male, or pollen, parent.—Proprietary breeding selection of *Mandevilla sanderi* identified as code number D14-3060-1, not patented.

Propagation:

Type.—By vegetative cuttings.

Time to initiate roots, summer and winter.—About three weeks at temperatures ranging from 20 C to 35 C.

Time to produce a rooted young plant, summer.—About 20 to 25 days at temperatures ranging from 20 C to 35 C.

Time to produce a rooted young plant, winter.—About 25 to 30 days at temperatures ranging from 20 C to 25 C.

Root description.—Thick, fleshy; typically white in color, actual color of the roots is dependent on substrate composition, water quality, fertilizers, substrate temperature and physiological age of roots.

Rooting habit.—Low branching; medium density.

Plant description:

Plant and growth habit.—Compact to medium in size, broadly upright plant habit; roughly broadly oblong to obovate in overall shape; moderately vigorous growth habit and moderate growth rate; and freely branching habit; dense and bushy appearance.

Plant height, soil level to top of foliar plane.—About 26.7 cm.

Plant height, soil level to top of floral plane.—About 27.1 cm.

Plant diameter (spread).—About 21.2 cm.

Lateral branch description.—Branching habit: Freely branching habit, typically about four lateral branches per plant; pinching enhances lateral branch development. Length: About 13.7 cm. Diameter: About 3 mm. Internode length: About 3 cm. Aspect: Erect to about 30 degrees from vertical. Strength: Strong. Texture and luster: Smooth, glabrous; slightly glossy; becoming woody with development. Color,

developing and developed: Close to 144A; when woody, close to N199A to N199D.	
Leaf description:	
<i>Arrangement</i> .—Opposite, simple.	
<i>Length</i> .—About 7.7 cm.	5
<i>Width</i> .—About 4.2 cm.	
<i>Shape</i> .—Broadly ovate to broadly elliptic and broadly obovate.	
<i>Apex</i> .—Short apiculate.	
<i>Base</i> .—Obtuse to rounded.	10
<i>Margin</i> .—Entire.	
<i>Texture and luster, upper surface</i> .—Smooth, glabrous; slightly coriaceous; moderately glossy.	
<i>Texture and luster, lower surface</i> .—Smooth, glabrous; slightly coriaceous; moderately glossy to glossy.	15
<i>Venation pattern</i> .—Pinnate.	
<i>Color</i> .—Developing leaves, upper surface: Close to a blend of 137A and 143A; edges, close to 175B. Developing leaves, lower surface: Close to 147B; edges, close to 175C. Full expanded leaves, upper surface: Darker than a blend of NN137A and 147A; venation, close to 143C. Fully expanded leaves, lower surface: Close to 146B; venation, close to 145C.	20
<i>Petioles</i> .—Length: About 1 cm. Diameter: About 2 mm by 2 mm. Strength: Moderately strong. Texture and luster, upper and lower surfaces: Smooth, glabrous; moderately glossy. Color, upper surface: Close to 145A; margins, close to 144A. Color, lower surface: Close to 144C; margins, close to 144B.	25
Flower description:	
<i>Flower type and flowering habit</i> .—Single salverform flowers arranged in terminal and axillary cymes; flowers face outwardly to slightly upright; freely flowering habit with about three or four flowers per inflorescence and about 18 flower buds and open flowers developing per plant during the flowering season.	30
<i>Natural flowering season</i> .—Plants flower continuously from spring into the autumn in Germany; plants begin flowering about ten weeks after propagation (dependent on light level).	35
<i>Flower longevity on the plant</i> .—Individual flowers last about ten days; flowers not persistent.	40
<i>Fragrance</i> .—None detected.	
<i>Inflorescence height</i> .—About 12.5 cm.	
<i>Inflorescence diameter</i> .—About 9.2 cm.	
<i>Flower buds</i> .—Length: About 5.3 cm. Diameter: About 8 mm. Shape: Narrowly obovate. Texture and luster: Smooth, glabrous; slightly glossy. Color: Distally, close to 187B; mid-section, close to 46A; proximally, close to 145A.	45
<i>Flowers</i> .—Appearance: Flared trumpet, corolla fused and five-parted. Diameter: About 7.8 cm by 7.8 cm. Depth (length): About 6.5 cm. Throat diameter: About 1.3 cm. Tube length: About 4.7 cm. Tube diameter: Proximally, about 4 mm; distally, about 1.5 cm.	50
<i>Corolla</i> .—Quantity and arrangement: Five petals arranged in a single whorl; lower 54% portion of the petals are fused into a funneliform tube. Petal length, free lobes: About 4 cm. Petal width, free lobes: About 3 cm. Petal shape and appearance: Unequal broadly spatulate; slightly convex. Petal apex: Short apiculate, unequal. Petal margin: Entire; moderately undulate. Petal texture and luster, upper surface: Smooth, glabrous; velvety; slightly glossy. Petal	55

texture and luster, lower surface: Smooth, glabrous; slightly velvety; slightly glossy. Throat texture: Smooth, glabrous; velvety. Tube texture: Smooth, glabrous; slightly velvety. Color: Petal, when opening, upper surface: Close to 187C. Petal, when opening, lower surface: Close to 46A and 187C. Petal, fully opened, upper surface: Darker than 53A; towards the throat, slightly lighter than 53A; venation, similar to lamina; color does not fade with subsequent development. Petal, fully opened, lower surface: Close to 46A and 53A; venation, close to 46A and 53A; color does not fade with subsequent development. Throat: Distally, close to 34B; at the base of the throat, close to 151A; venation, similar to lamina colors. Tube: Close to N45A and 46A; distally, close to a blend of 145B and 145C and at the base, tinged with close to N170B; venation, similar to lamina colors.	
<i>Sepal</i> .—Quantity and arrangement: Five sepals arranged in a single whorl. Length: About 9 mm. Width: About 2 mm. Shape: Lanceolate. Apex: Narrowly acuminate. Base: Broadly cuneate and fused. Margin: Entire. Texture and luster, upper surface: Smooth, glabrous; slightly glossy. Texture and luster, lower surface: Smooth, glabrous; matte. Color: When developing, upper surface: Close to 144B; towards the margins, close to 144C; towards the apex, close to 182D. When developing, lower surface: Close to 144B; towards the apex, close to 182D. Fully opened, upper surface: Close to 145C to 145D; towards the apex, close to 182A. Fully opened, lower surface: Close to 144B; towards the apex, close to 182A.	
<i>Peduncles</i> .—Length: About 5.6 cm. Diameter: About 2 mm. Strength: Strong. Aspect: About 30 degrees from lateral branch axis. Texture and luster: Smooth, glabrous; glossy. Color: Close to 143A.	
<i>Pedicels</i> .—Length: About 1.7 cm. Diameter: About 2 mm. Strength: Strong. Aspect: About 30 degrees from peduncle axis. Texture and luster: Smooth, glabrous; moderately glossy. Color: Close to 144B.	
<i>Reproductive organs</i> .— <i>Stamens</i> : Quantity and arrangement: Typically five; basifixed; anthers coninvent. Filament length: About 2 mm. Filament color: Slightly lighter than 153D. Anther shape: Narrowly oblong. Anther size: About 1.25 mm by 9 mm. Anther color: Close to 162C. Pollen amount: None observed. <i>Pistils</i> : Quantity: Typically one. Pistil length: About 2.2 cm. Style length: About 8 mm. Style color: Close to 145C. Stigma diameter: About 2 mm. Stigma shape: Club-shaped, pointed. Stigma color: Close to 146D. Ovary color: Close to 143C.	
<i>Seeds and fruits</i> .—To date, seed and fruit production have not been observed on plants of the new <i>Mandevilla</i> .	
Pathogen & pest resistance: To date, plants of the new <i>Mandevilla</i> have not been noted to be resistant to pathogens and pests common to <i>Mandevilla</i> plants.	
Temperature tolerance: Plants of the new <i>Mandevilla</i> have been observed to tolerate temperatures ranging from about 5 C to about 40 C and to be suitable for USDA Hardiness Zones 9 to 13.	
It is claimed:	
1. A new and distinct <i>Mandevilla</i> plant named 'Inmanbeamag' as herein illustrated and described.
